PROPELLING PENCIL

Lodovico Kraemer, Milan, Italy

Application September 28, 1937, Serial No. 166,055
In Italy October 1, 1936

2 Claims. (Cl. 120—19)

The present invention refers to an automatic locking device for lead pencils sliding in the barrel.

This particular device serves to lock the magazine, relative to its support in any position, either in writing position, or in retracted position.

The locking device consists of a slider serving as support for the lead for example to an elastic socket or to a spring carrying the lead, this slider being provided on the inside with a wedging member for example a ball which can be used by a spring along an inclined plane of this slider in such a manner as to produce, in co-operation with the internal surface of the barrel of the pencil, a constant contact of the ball between this plane and this surface.

The slider has the shape of a shuttle with a plane inclined from the front towards the rear for a short distance of the bottom of this slider which has at the rear a wall against which the spring abuts.

To cause the lead to project outside the barrel use is made of a sleeve mounted on the barrel and provided with a wing which projects through a longitudinal slot in the barrel, towards the interior of the latter and exactly in the space between the inclined plane and the ball serving for the wedging. The wing of this sleeve in pushing against the inclined plane pushes forward the slider with the support for the lead.

During this forward movement of the slider the ball tries to descend along the inclined plane by the amount which suffices to avoid all wedging.

In order to retract the lead the socket is pulled backwards and then the internal wing prevents the wedging of the ball and pulls back the slider towards the rear by the intermediation of a spring.

The locking device formed by the spring, by the ball, by the inclined plane of the slider and by the internal surface of the barrel remains in normal condition always ready to function.

The invention will be readily understood with the aid of the following detailed description which refers to the annexed drawings of one form of construction given by way of example only.

Fig. 1 shows the sliding lead pencil, provided with the new locking device, in perspective view; Fig. 2 shows a fragmentary longitudinal section, the operating ring being omitted; Fig. 3 shows the working of the locking whilst the lead is being retracted; Fig. 4 shows the working of the pencil while the lead is being advanced; Fig. 5 shows a transverse section on the line A—B of Fig. 4; Fig. 6 is a transverse section on the line

C—D of Fig. 3; Fig. 7 is a transverse section on the line E—F of Fig. 3.

Figs. 8—16 show a sliding lead pencil provided with a different construction of locking device and more exactly:

Fig. 8 shows a perspective view of the pencil; Fig. 9 shows a section of the pencil while the ring is drawn back with a view to retracting the lead; Fig. 10 shows a section during the pushing forward of the lead; Fig. 11 shows on a larger scale the wedging disc in two positions; Fig. 12 shows the transverse section of the barrel; Fig. 13 shows an axial section of the ring which moves the lead; Fig. 14 shows a transverse section of the moving tongue mounted on the barrel and surrounded by a ring which moves it; Fig. 15 shows the wedging disc; Fig. 16 shows a perspective view of the tongue with its two wings.

Referring particularly to the figures of the drawings:

1 is the barrel of the pencil provided with a longitudinal slot; 3 is a slider in the shape of a shuttle having a base provided with a sloping surface 4.

In the hollow of this shuttle is housed a spiral spring 6 which abuts against a ball 7 and against the rear wall 5 of the shuttle. The ball 1 cannot reascend completely the length of the inclined surface 4, because up above it meets the internal surface of the barrel 1. This wedging produces a transverse thrust on the shuttle 3 which sticks energetically against the barrel. The spring 6 pressing against the ball 7 assures the locking action of the shuttle in all positions with respect to the barrel 1. The sliding shuttle 3 may carry the lead 9 by means of a very flexible metal spiral spring 10. This spiral spring serves to assure the flexibility of support of the lead during writing.

In order to advance the lead a ring 11 is provided slidably mounted on the barrel 1 and provided with an internal, radially directed tongue 12, and traversing the slot 2 which serves as a guide.

This tongue 12 during its longitudinal movements may abut against the inclined plane 4 (Fig. 4) and it moves the shuttle 3 forwards and thereby also the lead 9. If on the other hand the ring 11 moves back, the tongue 12 pushes the ball 7 which, by the intermediation of the spring 6, abutting against the wall 5, pushes the shuttle 3 backwards, as the ball 7 ceases to wedge energetically against the internal surface of the barrel 1.

The lead-carrying spiral spring 10 may also be

replaced by another member, elastic, semi-elastic or rigid.

The barrel of the pencil may also have any other shape different from the cylindrical form with point. The shuttle may also have a form different from that indicated provided that the wedging device is substantially the same.

According to the construction shown in Figs. 8-16:

10 13 is a tongue introduced into the slot 2' and supported by two wings 13, 13a, 13b, on the barrel 1'; 12' is a moving ring with two internal flanges 12'a, 12'b, serving to move the tongue 13. This tongue 13 projects into the shuttle 3' of 15 which the rear wall 5' is brought very close to the tongue 13.

A slight movement of this tongue is sufficient to encounter the disc 14 which finally encounters the wall 5'.

20 When the pencil is inclined with its point downwards, the surface of the disc 14 touches the internal wall of the barrel 1' and if the point is supported on the paper, the inclined plane 15 produces its wedging. In this position the disc 14 25 passes into the position 14' and produces the effect of locking the shuttle 3' against the internal wall of the barrel.

This construction is more economical because it does away with the spring, and because the 30 disc 14 may be made by cutting from a sheet.

I claim:

1. In a mechanical pencil, a longitudinally slotted casing, a lead holder provided with a tapered surface slidably arranged within said casing, a clamping roller arranged between the inner wall of said casing and tapered surface of said holder, a ring member with an inner projection slidably mounted upon the slotted casing, the projection passing through the casing slot and entering the zone between said roller and apex of the tapered surface of said lead holder in order to disengage said roller from its clamping position on retracting of said ring member. 10

2. In a mechanical pencil, a longitudinally slotted casing, a lead holder with a tapered surface 15 slidably arranged in said casing, a clamping roller arranged between the inner wall of said casing and tapered surface of said holder, a ring member provided with an inner circular groove slidably mounted upon said casing, a curved 20 sheet metal strip with an inner projection arranged in the groove of the ring, the inner projection of said strip passing through the casing slot and entering the zone between said roller and apex of the tapered surface of said roller adapted to disengage said roller from its clamping position on retracting of said ring member. 25
